UNITED STATES PATENT OFFICE.

EUGENE T. GRANBERY, OF NEW YORK, N. Y.

MACHINE FOR TRANSFERRING MAIL-BAGS.

SPECIFICATION forming part of Letters Patent No. 677,978, dated July 9, 1901.

Application filed June 23, 1900. Serial No. 21,296. (No model.)

To all whom it may concern.

Be it known that I, EUGENE T. GRANBERY, a citizen of the United States, residing at No. 29 West Fifty-third street, New York city, 5 borough of Manhattan, State of New York, have invented new and useful Improvements in Machines for Transferring Mail-Bags to and from Railroad-Trains while the Trains are in Motion, of which the following is a specification.

My invention relates to improvements in machines by means of which mail-bags may be safely transferred from a moving train to a designated place along the railroad and at 15 the same time another mail-bag may be picked up at the said place and taken on board the moving train; and the objects of my invention are, first, to provide such a machine that will operate to a certain extent automatically, 20 as more fully set forth below, and, second, to afford facilities not only to pick up mail-bags from a designated place along the railroad, but in addition and at the same time to transfer mail-bags with safety from the moving 25 train to the said designated place along the road. I attain these objects by the mechanism illustrated in the accompanying drawings, in which—

Figure 1 represents practically the entire 30 machine, part erected at the designated place and part affixed to the car, before it is thrown into position to operate. Fig. 2 represents the same machine (the car and track and part of the post left out for simplicity) after it is 35 in position to operate. Fig. 3 represents another view of the machine with the mail-bags in place and machine in position to operate. Fig. 4 represents a side view of the catch which holds the part of the machine attached to the 40 car in its ordinary position until released by the operation of the automatic device. Fig. 5 is a detail of the device attached to the car, giving the same view of the elements detailed and in same position as shown in Fig. 1. Fig. 45 6 is a sectional view of the same elements of the device as is shown in Fig. 5 looking from a point in a line at right angles to the line of vision in Fig. 5. This view shows those elements after the machine is thrown into position to operate.

Similar letters refer to similar parts throughout the several views.

The post A, with the two arms *a a*, to which the mail-bag *b* may be attached by the station-master, and the fork *c*, also attached to post 55 A for receiving the mail-bag from the moving train, is erected at the edge of the railroad-track at the designated point where the change of mail-bags is to take place and at a proper distance from said track, so that it 60 will work in conjunction with the mechanism attached to the cars. This post must turn in the bearings *d d*, for which purpose a handle *e* is provided. At the foot of the post A is attached a short arm *f*. To the other end of 65 this short arm is attached a long shaft or double chain *g*, which extends along the edge of the track in the direction from which the cars are expected about two hundred or three hundred feet (more or less) and there connected 70 with one end of the elbow *h*. This elbow *h* turns on a pivot at *i*. The other end of this elbow is attached to the rod *j*, which works up and down in the bearings *k k*. This rod *j* must be so placed that when thrown up into 75 position, as shown in Figs. 2 and 3, it will engage the elbow *l*, this last elbow being part of the mechanism attached to the cars.

I shall now describe that part of the machine attached to the car.

80 B is a fork, which when in position grasps the mail-bag from the post A as the train rushes by. In its normal position, before the machine has been thrown into position to operate, the fork *B* lies flat against the side of the car. This fork *B* is firmly attached to the rod *C*, which turns in the bearings *m m m m*.

D is an arm, the shape of which is best shown in Figs. 3 and 6, also attached to the rod *C*. The arm *D* is that part of the device 90 to which the mail-clerk on the car attaches the mail-bag which is to be left at the way-side station. The relation of the elements *B*, *C*, and *D* to each other is best shown in Fig. 6. When the machine is not in position 95 to operate, *B* lies flat against the side of the car and the arm *C* extends inside the car. When in position to operate, *C* extends outside the car under the fork *B*, as shown in Figs. 3 and 6.

100 E is a catch on the end of the sliding rod *r*, which holds the rod *C* in its ordinary position, as shown in Fig. 1. This sliding rod *r* is controlled by the spring *n* and the elbow *l*.

This elbow *l* turns on the pivot *o* and is so placed that one end of it will engage the upper end of the rod *j* when the latter is thrown up into the second position, as described 5 above.

The catch *E*, as shown in Fig. 4, is so constructed that when the sliding rod *r*, to the upper end of which *E* is attached, is in its normal position the catch *E* holds the crank 10 *x* against the side of the car, and thus prevents the rod *C* from turning. The only way 15 in which *x* may be released is by drawing down *r* by means of the elbow *l*; but *x* may be locked by *E* while *r* is in its normal position.

s is a spring in the end of *r*, which holds the trip *t* parallel to and flat against *r*; but the action of returning *C* and *x* to their ordinary positions by the mail-clerk in the 20 car, after the mail-bags have been interchanged, will force *t* in the direction indicated by the arrow in Fig. 4 until *t* is clear of *x*, when *s* will force *t* back to its normal position and the mechanism will be set and ready for 25 use at the next station.

At *p* is shown a spring attached to a crank in the rod *C*, which when the rod *C* is released from the catch *E* turns the rod *C* and throws the fork *B* and the arm *D* out into the position shown in Figs. 2, 3, and 6, ready to pick up one bag and leave the other.

F shows the shield covering the spring *p*, (which in Fig. 1 is partly left out so that the spring *p* may be seen.) The crank in the rod 30 *C* to which the spring *p* is attached is so shaped that the rod *C* will only turn through an angle of ninety degrees.

The machine is worked as follows: The station-master places the outgoing mail-bag on 40 the two upper arms *a a* of post *A*, as shown in Fig. 1, then turns post *A* so that the two arms *a a*, with the mail-bag, extend out toward the track at right angles to its former position, as shown in Figs. 2 and 3. This also 45 throws the fork *c* into position for receiving the mail-bag from the train, and at the same time the rod *j* is thrown up into position shown in Figs. 2 and 3, ready to engage the elbow *l* when the car passes. Before the car 50 reaches this point, the mail-clerk on the train places his mail-bag on the arm *D*. When the car passes the rod *j*, that rod engages one end of the elbow *l*, which, turning on its pivot, pulls down the catch *E* and releases the rod *C*, 55 which, turning (moved by spring *p*) through an arc of ninety degrees, throws the fork *B* and the arm *D* out into position to operate in connection with that part of the machine erected at the wayside station. This position of *B* and *D* is shown in Figs. 2, 3, and 6. The elbow *l* then being free of the rod *j* (the car having passed that point) it is returned to its normal position by the spring *n*. As 60 the fork *B* and the arm *D* pass the post *A* the mail-bag attached to post *A* becomes wedged in the fork *B*, and being only lightly fastened to post *A* remains in *B*, and at the same time

the mail-bag fastened to arm *D* becomes wedged in fork *c* and in the same way remains there. Thus the two bags are exchanged, as desired. The rod *C* may then be turned into its ordinary position, where it is locked and held in place by catch *E* on the end of sliding rod *r*, which is now in its normal position, and the mail-bag which has 70 been picked up may be removed from fork *B*. When not intended to be used, the post *A* should be kept in the position shown in Fig. 1.

I am aware that prior to my invention a device similar to fork *B* has been used to pick 80 up mail-bags from a post similar to post *A*. I therefore do not make any claim as to that particular portion of my machine by itself; but

What I do claim as my invention, and desire to secure by Letters Patent, is—

1. In a machine for transferring mail-bags to and from moving trains, an arm *D* for holding a mail-bag to be delivered, attached to a rod *C* which turns in bearings on the side of 90 the car, a spring so connected as to tend to turn said rod and to throw said arm out into position to deliver the mail-bag and a device consisting of a catch on the end of a sliding rod attached to a pivoted elbow, so disposed 95 that said catch holds the rod *C* in a position with arm *D* inside the car, said device adapted to be operated in connection with ground mechanism whereby rod *C* is released and, turning, arm *D* is thrown out into position to deliver the mail-bag, substantially as set forth and described.

2. In a machine for transferring mail-bags to and from moving trains, a fork *B* for grasping a mail-bag from a post by the wayside, attached to a rod *C* which turns in bearings on the side of the car, a spring so connected as to tend to turn said rod and throw said fork out into position to grasp the mail-bag and a device consisting of a catch on the end 100 of a sliding rod attached to a pivoted elbow, so disposed that said catch holds the rod *C* in a position with fork *B* flat against the side of the car, said device adapted to be operated in connection with ground mechanism, whereby rod *C* is released and turning, fork *B* is thrown out into position to grasp the mail-bag from the post at the wayside, all substantially as set forth and described.

3. In a machine for transferring mail-bags 120 to and from moving trains, an arm *D* for holding a mail-bag to be delivered and a fork *B* for grasping a mail-bag from a post by the wayside attached to a rod *C* which turns in bearings on the side of the car, a spring so 125 connected as to tend to turn said rod and throw said arm for holding the mail-bag out into position to deliver the mail-bag and at the same time throw said fork *B* out into position for grasping a mail-bag from the post by the 130 wayside, and a device consisting of a catch on the end of a sliding rod attached to a pivoted elbow, so disposed that said catch holds the rod *C* in a position with arm *D* inside the

car and fork B flat against the side of the car, said device adapted to be operated in connection with ground mechanism, whereby rod C is released and turning, arm D is thrown 5 out into position to deliver the mail-bag and at the same time fork B is thrown out into position to grasp a mail-bag from the post by the wayside, all substantially as set forth and described.

- 10 4. In a machine for transferring mail-bags to and from moving trains, a rotating post A connected by a short arm and long shaft or double chain with a pivoted elbow, to one end of which elbow is attached a sliding rod which, when post A is turned, is adapted to engage with trip mechanism on the passing car con- 15 sisting of a pivoted elbow and sliding rod on the end of which is a catch, whereby said catch is withdrawn, allowing device on the car for catching and delivering mail-bags to operate automatically, all substantially as set 20 forth and described.
- 5. In a machine for transferring mail-bags

to and from moving trains, a rotating post A 20 connected by a short arm and long shaft or double chain with a pivoted elbow, to one end of which elbow is attached a sliding rod which, when post A is turned, is adapted to engage with trip mechanism on the passing car con- 25 sisting of a pivoted elbow and sliding rod on the end of which is a catch, whereby said catch is withdrawn, allowing device on the car for catching and delivering mail-bags to operate automatically, all substantially as set 30 forth and described.

In testimony whereof I have signed my name to this specification in the presence of two subscribing witnesses.
